UNITED STATES PATENT OFFICE.

BURTNELL MCINTOSH, OF BROOKLYN, NEW YORK, ASSIGNOR TO FRANK A. HALL, OF MONTCLAIR, NEW JERSEY.

BED-BOTTOM OR THE LIKE.

1,242,960.

Specification of Letters Patent.

Patented Oct. 16, 1917.

Application filed January 18, 1916. Serial No. 72,662.

To all whom it may concern:

Be it known that I, BURTNELL MCINTOSH, a citizen of the United States, residing at Brooklyn, in the county of Kings and State of New York, have invented certain new and useful Improvements in Bed-Bottoms or the like, of which the following is a specification.

This invention relates to a support and is particularly useful when employed as a mattress support in hospitals for the wounded under circumstances when it is necessary to positively or rigidly support the patient's body at all points, that is in such a way as will not permit any downward yielding movement such as is possible with bedsprings as usually constructed.

Among the objects of my invention is to provide a support of very simple construction which can be made quite rigid throughout and which would operate to support a mattress unyieldingly as suggested above. I provide supporting means to extend under the mattress and provide simple means for placing the supporting means in tension to render it rigid.

In the drawing, Figure 1 is a plan of a mattress support embodying my invention and showing the same before the parts are brought into their final relation of rigidity; Fig. 2 is a plan of a mattress support shown in Fig. 1 but with the parts in their final state of rigidity; Fig. 3 is a detail and is a vertical section taken on the line 3—3 of Fig. 2.

The support preferably comprises supporting means to extend under the mattress consisting of a plurality of longitudinal members 1 and transverse members 2. These members are preferably in the form of relatively thin flat strips popularly called "strap iron", and they are preferably woven together to produce a wide mesh such as illustrated.

I provide means for exerting tension in this supporting means. For this purpose I prefer to provide a pair of oppositely disposed resilient bars 3, 3 which are preferably formed originally as slightly bowed bars, see Fig. 1, disposed with their concave sides toward the woven members 1 and 2.

The supporting means such as the woven members 1 and 2 is preferably connected at a plurality of points to the bars 3 by means

of tension devices connected respectively with the ends of the longitudinal members

1. These tension devices are preferably simply adjusting screws 4 clamped to the ends of the longitudinal straps 1 and passing loosely through the bowed bars to receive nuts 5, which when tightened up will evidently flex the bowed bars toward a substantially straight line, see Fig. 2, and thereby cause the bowed bars to exert tension in the members 1.

I provide means for developing tension in the supporting means in another or transverse direction. In order to accomplish this I prefer to provide side bars 6, 6 which are attached to the ends of the bars 3, 3 and also attached at a plurality of points to the supporting means. In the present embodiment the ends of the transverse members 2 are attached to the bars 6.

When the bars 3, 3 are flexed (by tightening the nuts 5) toward a substantially straight line, the effective length of the bars 3, 3 increases, and this of course exerts a spreading force upon the bars 6, 6. This places the members 2 in tension. As the tension in the members 2 might tend to bow the side bars 6, 6 and thus relieve the tension in the members 2, I prefer to provide means for counteracting this effect, and at the same time to assist in exerting tension in the members 2. For this purpose I prefer to provide inclined struts or diagonal braces 7 at the corners, which connect intermediate points of the bars 3 and 6. When the bowed bars 3 straighten out or approach their straight condition, the struts 7 exert an outward thrust and cause a slight outward movement or spreading movement of the middle portions of the side bars 6. Hence the diagonals perform a double function of preventing an inward movement of the sides 6 and actually produce an outward movement of the sides.

It is understood that the embodiment of the invention described above is only one of the many forms or embodiments the invention may take and I do not wish to be limited in the practice of my invention nor in my claims to the particular embodiment set forth.

I claim:

1. A mattress support comprising supporting means to extend under the mattress,

side bars attached to said supporting means, a bowed bar, a connection between the bowed bars and the side bars, and means connecting said bowed bar and said supporting means at a plurality of points for flexing said bar toward a substantially straight form and thereby developing tension in said supporting means.

2. A mattress support comprising supporting means to extend under the mattress, side bars attached to said supporting means, a resilient bowed bar, a connection between the bowed bar and the side bars, means connecting said bowed bar and said supporting means at a plurality of points for flexing said bar toward a substantially straight form and thereby developing tension in said supporting means.

3. A mattress support comprising supporting means to extend under the mattress, side bars attached to said supporting means, a resilient bowed bar disposed with its concave side toward said supporting means, a connection between the bowed bar and the side bars, means connecting said bowed bar and said supporting means at a plurality of points for flexing said bar toward a substantially straight form and thereby developing tension in said supporting means.

30 4. A mattress support comprising supporting means to extend under the mattress, a resilient bowed bar, means connecting said bar and said supporting means at a plurality of points on said bar, for flexing said bar toward a substantially straight form and thereby developing tension in said supporting means in one direction, and means for imparting force from said bar to said supporting means transversely to exert tension in said supporting means in another direction.

5. A mattress support comprising supporting means to extend under the mattress, bowed resilient bars, means connecting said bars and said supporting means at a plurality of points on said bar for flexing said bars toward a substantially straight form and developing tension in said supporting means in one direction, side bars attached to said supporting means at a plurality of points, and attached to said resilient bars to receive a spreading force from said resilient bars to impart tension to said supporting means in another direction.

55 6. A mattress support consisting of supporting means to extend under the mattress, side bars attached to said supporting means, a pair of oppositely disposed bowed bars, a connection between the bowed bars and the side bars, and means connecting said bowed bars and supporting means at a plurality of points for flexing said bars toward a sub-

stantially straight form and thereby exerting tension in said supporting means.

7. A mattress support consisting of supporting means to extend under the mattress, a pair of oppositely disposed bowed bars, means connecting said bars and said supporting means at a plurality of points along said bars for flexing said bars toward a substantially straight form and exerting tension in said supporting means, side bars attached to said supporting means, and inclined struts connecting said bowed bars and said side bars for imparting force from said bowed bars to said side bars to exert tension transversely in said supporting means.

8. A mattress support consisting of supporting means to extend under the mattress consisting of a plurality of longitudinal and transverse members, a pair of oppositely disposed bowed bars, means connecting said bars and said supporting means at a plurality of points along said bars for flexing said bars toward a substantially straight form and exerting tension in said supporting means, side bars attached to said supporting means, and inclined struts connecting said bowed bars and said side bars for imparting force from said bowed bars to said side bars to exert tension transversely in said supporting means.

9. A mattress support consisting of a plurality of longitudinal and transverse members, a pair of oppositely disposed resilient bowed bars, side bars abutting against the ends of the bowed bars and connected to the transverse members, means connecting said bowed bars and said longitudinal members at a plurality of points on said bowed bars for flexing said bowed bars toward a substantially straight form and exerting tension in said longitudinal members, and imparting a spreading force from said bowed bars to exert tension in said transverse members.

10. A mattress support consisting of a plurality of longitudinal and transverse members, a pair of oppositely disposed resilient bowed bars, tension devices connecting said longitudinal bars respectively with said bowed bars at a plurality of points on said bowed bars, for flexing said bowed bars toward a substantially straight form and exerting tension in said longitudinal members, side bars attached to said transverse members, and diagonal bars connecting intermediate points on said side bars and said bowed bars to impart force from said bowed bars to said side bars and thereby exert tension in said transverse members.

In testimony whereof I affix my signature in presence of two witnesses.

BURTNETT MCINTOSH.
